UNITED STATES PATENT OFFICE.

LOUIS H. THULLEN, OF EDGEWOOD PARK, PENNSYLVANIA, ASSIGNOR TO THE UNION SWITCH & SIGNAL COMPANY, OF SWISSVALE, PENNSYLVANIA, A CORPORATION OF PENNSYLVANIA.

SIGNAL SYSTEM FOR RAILWAYS.

No. 890,197.

Specification of Letters Patent.

Patented June 9, 1908.

Application filed August 22, 1904, Serial No. 221,772. Renewed September 26, 1905. Serial No. 280,176.

To all whom it may concern:

Be it known that I, LOUIS H. THULLEN, a citizen of the United States, residing at Edgewood Park, in the county of Allegheny and State of Pennsylvania, have invented certain new and useful Improvements in Signal Systems for Railways, of which the following is a specification.

My invention relates to signaling systems and particularly to the application of such systems to electric railways.

I will describe a signaling system embodying my invention and its application to an electric railway and then point out the novel features thereof in claims.

In the accompanying drawing, Figure 1 is a diagrammatic representation of an electric railway, and a signaling system embodying my invention applied thereto. Figs. 2 and 3 are each detail views showing modified forms of a device or piece of apparatus involved in my invention.

Similar letters of reference designate corresponding parts in all of the figures.

Referring now to the drawings, A designates a portion of a railway in which both lines of rails are provided with insulation a^1 at suitable points whereby the railway is divided into "track" or "block sections" in a manner well understood in the art. I have shown one such track section, as I shall hereinafter term them, a , and portions of two adjacent track sections a^1 , a^2 .

B designates a generator, which may be a direct current generator or an alternating current generator as desired, for generating current for the propulsion of cars or vehicles along the railway. It is here shown as a direct current generator. One pole of the generator is connected in the usual manner with a line conductor b along which travel the trolleys or shoes w carried by the cars or vehicles. W is an arbitrary representation of a car or vehicle. The other pole of the generator B is connected with both track rails in the usual or ordinary manner. As shown it is connected with a cross bond b^2 shown in the form of an inductive winding.

In order that the track rails may be employed as a return for the propulsion current, I provide inductive or impedance windings D , D^2 at the ends of each track section and electrically connected the middle points of the coils on adjacent windings with each

other. Each inductive winding comprises a magnetic current d and a divided coil or two coils d^1 , d^2 , joined together to form a single coil which coil or coils are arranged on a leg of the magnetic circuit in such manner that any current flowing into its ends and out at its middle point or in at its middle point and out at its ends will not have impaired the magnetic circuit of the inductive winding to such an extent as to impair its efficiency as an impedance to the flow of an alternating current through the coil in a single direction. The function of these windings, their relative arrangement and the electrical connections between adjacent coils at their middle points is set forth in my co-pending applications filed February 5th, 1904, Serial Nos. 192,145 and 192,146. The present invention relates more particularly to the construction of the inductive windings, and particularly to the magnetic circuit of such windings. I preferably arrange the core or construct it so that the magnetic circuit is formed in part by a substance having high permeability, such as steel or iron, and a substance of low permeability such as, wood or brass. The object of so forming the cores is as follows: The propulsion current returning from the motors will divide itself equally between the track rails and the several inductive windings provided the ohmic resistance is the same in the rails and the inductive windings. As it is possible and probable that the resistance in both track rails will not be the same on account of imperfect bonding etc., it becomes necessary to provide against saturation or high magnetization of the cores of the inductive windings by the propulsion current traversing the coils in unequal proportions, for should they become saturated or highly magnetized the inductive windings will not effectively act as impedance to the track circuit current. I therefore so form the cores as to increase the reluctance of the magnetic circuit of the core, thereby keeping the iron or other material composing the core from becoming highly magnetized or saturated. For instance; suppose that through defective joints or bonding one track rail is made to conduct more propulsion current than the other, then the difference between the current carried by the two track rails would represent the current tending to magnetize the cores of the

inductive windings. If the magnetic circuit of the cores of the inductive windings is composed partly of iron and partly of some other substance of low permeability, the cores will 5 not become saturated by any reasonable amount of current traversing the winding. The amount of current that could be made to traverse the windings without saturating the cones would depend upon the length of 10 the air gap or the reluctance through the magnetic circuit of each core. Therefore I have designed these inductive windings, the cores of which are composed of iron, steel or other material of high permeability or small 15 reluctance to the magnetic lines of force, and partly of a substance such as wood or brass having a very low permeability or high reluctance to the magnetic lines of force.

I do not restrict myself to any material or 20 materials used in the construction of the cores of the inductive windings or any material known to the arts having the qualifications as stated above. These openings in the magnetic circuits or the substitution of 25 materials of low permeability can be made variable and adjustable to suit the conditions met with in practice. Figs. 2 and 3 illustrate inductive windings having different forms of cores.

30 F designates an alternating current generator, and f , f' feeder conductors extending therefrom and along the line of railway.

G, G' designate transformers, the primary windings of which are in multiple circuit with 35 the conductors f , f' while their secondary windings are connected with the track rails of the several track sections. At least one transformer is provided for each track section. Each track section is also provided 40 with a translating device or relay R which is in circuit with the track rails of its track section and is operated from the alternating current in the track section to control one indication of the railway signal by the alternating 45 current supplied from the transformer of that track section. Each translating device may be substantially of the form shown and described in my Patent No. 823,086, dated June 12, 1906.

50 Each track section is provided with a railway signal S which controls the passage of trains through the track section. Each railway signal is controlled through a local circuit from the translating device R of its 55 track section in a manner well known in the art, and comprises a signal device, which by its color or position relatively to its support gives indications of the service condition of the track section and mechanism which is 60 automatically or manually operated as is well known in the art.

What I claim as my invention is:

1. In a signaling system for electric railways, the combination with a plurality of 65 track sections, both rails of which are insu-

lated, a track circuit for each track section, a source of alternating current supply for each track circuit, a source of current for propelling the cars, the track rails of the track sections forming a return path therefor, and means between adjacent track sections for permitting propulsion current to pass from the track rails of one track section to the track rails of another track section, and having a magnetic circuit composed of more 75 than one substance. 70

2. In a signaling system for electric railways, the combination with a plurality of track sections, both rails of which are insulated, a track circuit for each track section, a source of alternating current supply for each track circuit, a source of current for propelling the cars, the track rails of the track sections forming a return path therefor, and means between adjacent track sections for permitting 80 propulsion current to pass from the track rails of one track section to the track rails of another track section and having a magnetic circuit composed partly of metal and partly of another substance. 85

3. In a signaling system for electric railways, the combination with a plurality of track sections, both rails of which are insulated, a track circuit for each track section, a source of alternating current supply for each 95 track circuit, a source of current for propelling the cars, the track rails of the track sections forming a return path therefor, and means between adjacent track sections for permitting propulsion current to pass from the track rails of one track section to the track rails of another track section, and having a magnetic circuit composed partly of a magnetic substance and partly of a non-magnetic substance. 100

4. In a signaling system for electric railways, the combination with a plurality of track sections, both rails of which are insulated, a track circuit for each track section, a source of alternating current supply for each 110 track circuit, a source of current for propelling the cars, the track rails of the track sections forming a return path therefor, and means between adjacent track sections for permitting the propulsion current to pass 115 from the track rails of one track section to the track rails of another track section, and having a magnetic circuit composed of substances of different permeabilities. 105

5. In a signaling system for electric railways, the combination with a plurality of track sections, both rails of which are insulated, a track circuit for each track section, a source of current for propelling the cars, the track rails of the track sections forming a return path therefor, and means between adjacent track sections for permitting the propulsion current to pass from the track rails of one track section to the track rails of another track section, and having a magnetic 125

120

130

circuit composed of substance of low permeability and a substance of high permeability.

6. In a signaling system for electric rail-
ways, the combination with a plurality of
track sections, both rails of which are insu-
lated, a track circuit for each track section, a
source of alternating current supply for each
track circuit, a source of current for propel-
10 ling the cars, the track rails of the track sec-
tions forming a return path therefor, and
means between adjacent track sections for
permitting propulsion current to pass from
the track rails of one track section to the
15 track rails of another track section, and hav-
ing a magnetic circuit composed of a sub-
stance of high permeability and a substance
of low permeability, said substance of low
permeability to be non-magnetic.
- 20 7. In a signaling system for electric rail-
ways, the combination with a plurality of
track sections, both rails of which are insu-
lated, a track circuit for each track section, a
source of alternating current supply for each
25 track circuit, a source of current for propel-
ling the cars, the track rails of the track sec-
tions forming a return path therefor, said
means being placed between the running rails
and formed of a plurality of turns around an
30 iron core, the magnetic circuit of which is
composed partly of a substance having a low
permeability and partly of a substance hav-
ing a high permeability, the substance of low
permeability to be non-magnetic.
- 35 8. In a signaling system for electric rail-
ways, the combination with a plurality of
track sections, both rails of which are insu-
lated, a track circuit for each track section, a
source of alternating current supply for each
40 track circuit, a source of current for propel-

ling the cars, the track rails of the track sec-
tions forming a return path therefor, and
a means at each end of the track section for
permitting the propulsion current to pass
from the track rails of one track section to 45
the track rails of another section and said
means being formed to be unaffected by the
passage of the propulsion current through it,
and having a core constituting a magnetic
circuit, of substances of different permea- 50
bilities.

9. In a signaling system for electric rail-
ways, the combination with a plurality of
track sections, both rails of which are insu-
lated, a track circuit for each track section, a 55
source of alternating current supply for each
track circuit, a source of current for propel-
ling the cars, the track rails of the track sec-
tions forming a return path therefor, and
means being placed between the running rails, 60
and formed of a winding and a magnetic cir-
cuit of more than one substance.

10. In a system of automatic block signal-
ing for electric railways and in combination
with the traffic rails each divided into block 65
sections by insulated joints, inductive wind-
ings each comprising a magnetic circuit com-
posed of more than one substance, and a
winding connected across the rails of the
block sections, and conductors connecting 70
the middle points of the coils of adjacent
inductive windings.

In testimony whereof I have signed my
name to this specification in the presence of
two subscribed witnesses.

LOUIS H. THULLEN.
